UNITED STATES PATENT OFFICE.

FRANK P. KOBERT, OF NEW HAVEN, CONNECTICUT.

BRACKET-ARM.

1,087,301.

Specification of Letters Patent. Patented Feb. 17, 1914.

Application filed January 31, 1913. Serial No. 745,330.

To all whom it may concern:

Be it known that I, FRANK P. KOBERT, a citizen of the United States, and residing at New Haven, in the county of New Haven and State of Connecticut, have invented certain new and useful Improvements in Bracket-Arms, of which the following is a specification, such as will enable those skilled in the art to which it appertains to make and use the same.

This invention relates to brackets and bracket arms for use as supports for electric cables in man holes and other places, and the object thereof is to provide an improved device or devices of this class involving an upright support and a bracket arm or arms adjustably connected therewith, the construction of the entire device and especially of the bracket arms being such as to give said arms the greatest possible strength in proportion to the amount of material employed; and with these and other objects in view, the invention consists in the construction, combination and arrangement of parts hereinafter described and claimed.

The invention is fully disclosed in the following specification of which the accompanying drawing forms a part, in which the separate parts of my invention are designated by suitable reference characters in each of the views, and in which;

Figure 1 is a longitudinal central vertical section through a bracket arm made according to my invention and through the support thereof; Fig. 2 a horizontal section on the line 2—2 of Fig. 1; Fig. 3 a plan view of a blank from which the main part of the bracket arm is made; Fig. 4 a view similar to Fig. 3, but showing the first step in the process of making the bracket arm from the blank shown in Fig. 3; Fig. 5 a side view of that part of the bracket arm shown in Fig. 4; Fig. 6 a view similar to Fig. 3, but showing a blank from which a heel piece forming part of the bracket arm is made; Fig. 7 a back and end view of said heel piece as formed ready for use from the blank shown in Fig. 6; Fig. 8 a back or bottom view of the bracket arm complete, as shown in Figs. 4 and 5, with the heel piece attached thereto, and indicating in dotted lines the method of finishing or trimming said arm into the form shown in Figs. 1 and 2; and; Fig. 9 a transverse vertical section on the line 9—9 of Fig. 1.

In the accompanying drawing Figs. 3, 4,

5 and 8 are on a scale much reduced from that shown in Figs. 1, 2, 6, 7 and 9.

In the accompanying drawing, I have shown at *a* a vertical support usually employed in manholes and station work for supporting bracket arms on which are placed electric cables, and in Figs. 1 and 2, I have shown at *b* my improved bracket arm for this purpose. The support *a* consists of a piece of channel-iron which, in practice is secured in a vertical position to a suitable frame work or other support placed in a manhole, and said channel-iron is provided at intervals with transverse slots or openings *a*² having downwardly directed extensions *a*³ of less transverse dimensions than the slots or openings *a*², and the bracket arm or arms *b*, any desired number of which may be employed, are provided with heads *b*² adapted to be passed backwardly through the slots or openings *a*², and said heads are provided with necks *b*³ adapted to be dropped downwardly into the extensions *a*³ of the slots or openings *a*², and by this means the bracket arm or arms *b* may be quickly and easily connected with and detached from the channel-iron support or supports *a*.

In forming a bracket arm *b* according to my invention, I take a strip *c* of sheet steel of predetermined thickness and which is preferably tapered from one end to the other, and formed therein by means of a suitable die mechanism is a central longitudinal groove *c*², this groove extends from the heel portion of the arm, or from adjacent to the head *b*² of the central part of said arm to within a predetermined distance from the free end thereof, as shown at *c*³, and the heel portion *c*⁴ of said groove is much deeper than the rest thereof, and the bottom of said groove tapers in depth from the heel portion *c*⁴ to the outer end portion *c*⁵ thereof or to the outer end portion of the arm, as clearly shown in Fig. 1. In forming the groove *c*² a corresponding rib *c*⁶ is formed on the bottom of the blank *c* and in forming said groove and rib in the die mechanism, as hereinbefore described, the sides of the strip *c* are contracted or drawn in, as shown at *c*⁶ in Fig. 4, and this contraction or drawing in of the sides of the said strip or blank extends from the head portion of the arm at *c*⁷ to the outer end of the groove *c*² at *c*⁸. I also provide the heel portion of the arm with a heel reinforcement *d* which is made from a blank *d*²,

shown in Fig. 6, and formed by means of a suitable die device or mechanism, as shown in Fig. 7, said blank being bent into a U-shaped form in cross section having side flanges d^3 .

The blank d^2 from which the heel piece d is formed is preferably the same in thickness as the blank c , and when formed in the manner described, the said heel piece is 10 placed on back of the heel portion of the arm b , as shown in Fig. 1, and as is also shown in Fig. 8, and is welded to said arm, after which the arm is placed in a finishing or shearing die and sheared off along the 15 dotted lines x of Fig. 8, and so as to form the head b^2 , as clearly shown in Fig. 2.

When the heel piece has been applied, as shown and described, and the arm connected with the support a , said heel piece bears 20 on said support and a bracket arm made as above described and as shown in the accompanying drawing, and if made of steel $\frac{3}{8}$ of an inch thick and 10 inches long will support over 200 lbs. at its outer end, and 25 this is about four times as much as such arms will support as usually constructed. It is also customary, in practice, for workmen, in going into and climbing out of manholes, to use the bracket arms that support 30 cables, and in this way said arms are frequently broken down, thus causing great damage and frequently causing injury to the workmen, but with my improved bracket arm or arms made, and supported in the 35 manner described, such accidents or results are obviated. Of course, the strength of the arm will depend upon the length there- 40 of and the thickness of the material em- ployed in its construction, but the great strength of my improved bracket arm or arms over other devices of this class as usually constructed, is the result of the tapered groove c^2 formed therein and the cor- 45 responding rib c^5 on the back or bottom of the arm, it being also understood that the

employment of the heel piece d also adds materially to the strength of the arm and the strain on the free end portion of the arm operates in the same manner as the strain on the arch. My invention is not 50 limited however, to the heel piece d nor to the length thereof, but in all cases where the greatest possible strength is required in the arm, the heel piece d should be employed. It will be observed that the free 55 end of the arm b is curved upwardly slightly, as shown at b^4 , and this result is produced at the same time that the groove c^2 and rib c^5 are formed.

Having fully described my invention what 60 I claim as new and desire to secure by Letters Patent is:—

A bracket arm of the class described the heel portion of said arm being provided with an attaching head whereby it may be 65 connected with a vertical support, and said arm being provided in the top surface thereof with a deep longitudinal groove forming on the back thereof a corresponding longitudinal rib, said groove being deepest at 70 the heel portion of said arm, and the depth thereof and the depth or thickness of said rib being tapered from the heel portion toward the free end portion of said arm, the heel portion of said arm being also provided with a heel piece which is welded to the bottom thereof and the form of which, in cross section, is similar to the form of the heel portion of said arm, said heel piece being adapted to bear on the support of 75 80 said arm substantially as shown and described.

In testimony that I claim the foregoing as my invention I have signed my name in presence of the subscribing witnesses this 85 30th day of January 1913.

FRANK P. KOBERT.
